UNITED STATES PATENT OFFICE.

GRANVEL FRANKLIN, OF FLINT, MICHIGAN.

RACK.

Application filed April 10, 1924. Serial No. 705,640.

To all whom it may concern:

Be it known that I, GRANVEL FRANKLIN, a citizen of the United States, residing at Flint, in the county of Genesee and State of Michigan, have invented certain new and useful Improvements in Racks, of which the following is a specification.

The present invention relates to a rack which may be used in various rooms of a 10 household for supporting various articles.

The prime object of the invention is to provide a rack which may be supported on the wall without the necessity of using nails or, the like which would injure the wall, 15 the device being provided with a structure capable of being held between two window frames or the like.

Another very important object of the invention is to provide a rack possessing a 20 simple and efficient construction, one which is reliable, inexpensive to manufacture, durable, attractive in appearance, and well adapted to the purpose for which it is designed.

25 With the above and numerous other objects in view as will appear as the description progresses, the invention resides in certain novel features of construction, and in the combination and arrangement of parts 30 as will be hereinafter more fully described and claimed.

In the drawing:

Figure 1 is an elevation of the rack embodying my invention and showing the manner in which the same may be mounted,

35 Figure 2 is an end elevation thereof,

Figure 3 is a fragmentary longitudinal section showing one end, and

40 Figure 4 is a detail transverse section on an enlarged scale taken substantially on the line 4-4 of Figure 1 looking in the direction of the arrow.

Referring to the drawing in detail it will be seen that the rack consists of an elongated 45 block or bar 1 and a comparatively short block or bar 2. A pair of bolts 3 pierce the block 2 and have their heads 4 countersunk in the outer end of the block. These 50 bolts 3 are slidably receivable in bores 5 extending longitudinally through the block 1. An opening 6 is provided adjacent one end 55 of the block 1 and a threaded bolt 7 extends longitudinally of the block 1 through the opening 6 and extends beyond the end of the block into the block 2. A plate 8 is fixed in the inner edge of the opening 6

and a nut 9 engaged with the bolt 7 is disposed in the opening 6 so as to bear against the plate 8 for forcing the block 2 away from block 1. The ends of the blocks are 60 provided with a plurality of staples 11 which may be arranged to advantage as shown in Figure 2 that is with the top and bottom staples substantially horizontal and the center staple substantially vertical. 65

The rack is placed between two window jams or a window jam and a door jam or between any two protrusions from the wall of a room and the nut 9 screwed upon the bolt 7 so as to bear against the plate 8 and 70 force the block 2 from block 1 so that the ends of the blocks may engage the projecting objects and the staples will thus be forced into sufficient frictional engagement therewith so as to hold the rack in place. 75 This all is accomplished without material injury or disfiguring of the objects or the wall.

In the present embodiment of the invention, I provide the bottom edge of the 80 elongated or body portion 1 with a series of hooks 13. An L-shaped member 14 is disposed with its shorter arm 15 rotatable in the top edge of the body block 1 so that its longer arm 16 may be swung horizontally 85 for the support of numerous articles. A plurality of hooks indicated generally at 17 are mounted on the upper edge of the body block 1 and are formed with an inverted U-shaped body 18 straddling the block held 90 in place by staples 19. One of the legs terminates in an upwardly extending member 20 forming the hook proper.

Although I have described the invention with a certain degree of particularity, it is 95 to be understood that numerous changes in the details of construction, in the materials, and in the combination and arrangement of parts may be resorted to without departing from the spirit or scope of the invention or 100 sacrificing any of its advantages.

Having thus described my invention, what I claim as new is:

1. A rack of the class described including an elongated body block, and a comparatively short auxiliary block, a pair of bolts projecting from the auxiliary block and slidably piercing one end of the body block, a threaded bolt engaging the auxiliary block and piercing the body block, said body block 105 provided with an opening, a bearing plate 110 in the opening, a nut threaded on the last

mentioned bolt within the opening so that said last mentioned bolt may be extended from the body block to force the auxiliary block therefrom, so that both of said blocks 5 may be pressed against the object for supporting the rack all in the manner and for the purpose specified.

2. A rack of the class described including an elongated body block, and a comparatively short auxiliary block, a pair of bolts 10 projecting from the auxiliary block and slidably piercing one end of the body block, a threaded bolt engaging the auxiliary block 15 and piercing the body block, said body block provided with an opening, a bearing plate in said opening, a nut threaded on the last mentioned bolt within the opening so that said last mentioned bolt may be extended from the body block to force the auxiliary 20 block therefrom so that both of said blocks may be pressed against the object for supporting the rack all in the manner and for the purpose specified, a plurality of staples 25 provided on the ends of the block for engaging the object.

3. A rack of the class described including an elongated body block, a comparatively short auxiliary block, a pair of bolts piercing the auxiliary blocks and having their heads countersunk therein, said bolts slidably piercing the body block, said body block provided with an opening, a longitudinally extending bore communicating with said opening, a threaded bolt movable 30 through the bore and engaged with the auxiliary block, a nut on the threaded bolt within the opening, a bearing plate within the opening so that said nut may be threaded to bear against the bearing plate thereby extending the threaded bolt to separate the auxiliary block from the body block, staples 35 arranged on the outer faces of the block to engage objects, and a plurality of hanging elements mounted on the body block.

In testimony whereof I affix my signature 40 in presence of two witnesses.

GRANVEL FRANKLIN.
